UNITED STATES PATENT OFFICE.

ELI BURNS, OF NEW KENSINGTON, PENNSYLVANIA.

BOTTLE.

932,956.

Specification of Letters Patent. Patented Aug. 31, 1909.

Application filed November 20, 1908. Serial No. 263,627.

To all whom it may concern:

Be it known that I, ELI BURNS, a citizen of the United States, residing at New Kensington, in the county of Westmoreland and State of Pennsylvania, have invented new and useful Improvements in Bottles, of which the following is a specification.

This invention relates to bottles, contemplating an improvement in bottles of that kind having controlling valves within the necks thereof to prevent or render difficult the operation of refilling the bottle with a different or inferior grade of liquid.

The object of the invention is to provide a bottle and controlling valve for the neck thereof which are simple of construction, easy and cheap to manufacture, and adapted to render the operation of refilling so difficult and to require so much time as to be unprofitable.

The invention consists of the features of construction, combination and arrangement of parts hereinafter fully described and claimed, reference being had to the accompanying drawing, in which:—

Figure 1 is a vertical section through the upper portion of the body and the neck of a bottle embodying my invention, showing the valve closed. Fig. 2 is a similar view of the bottle inverted for the discharge of its contents and with the valve open.

Referring to the drawing, 1 designates the body of a bottle, which may be of any preferred form, and 2 is the neck of the bottle, which is contracted at its lower end to form a valve-seat 3 and made of somewhat larger diameter at its mouth 4 to receive an ordinary closure cork or stopper, the body portion of the neck being outwardly bowed or swelled, as shown.

A ball-valve 5 is provided to engage the seat 3 and is movable within the neck. This valve is inserted initially through the mouth 4 and may be formed of metal or other suitable material, and either solid or hollow. It is of proper size to snugly drop down upon and engage the seat 3 by gravity and prevent the discharge of liquid from the bottle when the latter is erect. The valve will also float to its seat and close the neck against the in-

gress of liquid when the bottle is submerged or inverted, and it tends to close under other conditions when an attempt is made to introduce liquid, thus rendering the operation of refilling a difficult and tedious one. A suitable foraminous guard may be provided within the neck to prevent access to the valve by a wire or tool to hold the valve unseated.

A valve controlling device 6 is provided to regulate the movements of the valve. This is preferably formed of a single piece of wire, the end portions 7 of which are arranged in parallel relation and suitably secured to the head to form a shank, which supports a stop 8 formed by the central portion of the wire. This stop is of segmental form and is connected with the shank portions 7 by inturned offsets 9 and junction coils 10. The stop 8 as thus constructed is of greater length than the diameter of the seat outlet 3 and presents curved shoulders or flukes 11 adapted to engage the wall of the neck below said seat outlet to limit the opening movement of the valve.

It will be seen that the construction of the valve and its controlling device is such that the same may be initially inserted through the mouth 4 into the neck, and the controlling device forced, by its ability to contract, into the body of the bottle, but that as soon as the stop passes beyond the contracted seat it will expand so that its flukes 11 will effectually prevent its extraction. The construction and provision of the coils also insure a spring action, by which shocks and jars arising from forcible contact of the flukes with the bottle wall will be taken up and liability of injury to the parts prevented. By using a foraminous guard of the character described refilling of the bottle will be made practically impossible or rendered so difficult or tedious as to be unprofitable.

Having thus fully described the invention, what is claimed as new is:—

A bottle having a valve seat at the bottom of its neck, a valve movable in the neck toward and from said seat, and a resilient controlling device formed of wire bent to provide a shank composed of a pair of

spaced stems depending from the valve into the body of the bottle, a segmental-loop-shaped stop at the lower end of said shank, presenting upwardly curved hooked ends or 5 flukes to engage the body of the bottle at the base of the neck, the inwardly turned portions of said loop being connected with the lower ends of the stems, and spring coils in

10 said inturned portions at their juncture with the stems.

In testimony whereof I affix my signature in presence of two witnesses.

ELI BURNS.
